SAFETY DEVICE FOR FUSES

Robert G. Ferris, Harvard, Ill., and James D. Jordan, Washington, D. C., assignors to the United States of America as represented by the Secretary of the Navy

Application September 4, 1943, Serial No. 501,300

1 Claim. (Cl. 102—71)

1

This invention relates to safety devices for use in projectile fuses and has particular reference to a novel device of this character for normally blocking the firing train of a fuze and which is operable by centrifugal force, due to rotation of the projectile, to arm the fuze. The new safety device is simple and compact in construction, has relatively few moving parts and is positive in operation.

One object of the invention resides in the provision of a safety device for rotary projectile fuses, which comprises a pair of adjacent gates normally blocking the fuze firing train but each movable by centrifugal force in a direction substantially opposite to the direction of movement of the other, to arm the fuze.

Another object of the invention is to provide a safety device of the character described, in which the gates are normally locked in their safe or blocking positions by detents operable under centrifugal force to release the gates.

A further object of the invention is to provide a safety device for rotary projectile fuses, which comprises a body plate having an opening terminating in a slot, and a generally T-shaped gate in the plate having its head in the opening and its stem in the slot, whereby the gate normally blocks the fuze firing train but is movable in the plate as a guide by centrifugal force to arm the fuze. With this construction, the head of the gate provides a mass which is acted upon by the centrifugal force to actuate the gate, while the stem serves as a blocking element and is guided in its movement to the armed position by the plate slot. In the preferred construction, the gate is normally locked in its safe or blocking position by a detent in the plate projecting into a recess in the gate stem and movable by centrifugal force to release the gate.

Still another object of the invention is to provide in a fuze for a rotary projectile a centrifugally operated safety device for normally blocking the fuze firing train and which is characterized by its simplicity and compactness of construction.

These and other objects of the invention may be better understood by reference to the accompanying drawing, in which

Fig. 1 is a longitudinal sectional view of a fuze embodying one form of the invention;

Figs. 2 and 3 are sectional views on the lines 2—2 and 3—3, respectively, in Fig. 1, and

Fig. 4 is a sectional view on the line 4—4 in Fig. 3.

Referring to the drawing, the numeral 10 designates the outer can of an electrically operated fuze for a rotary projectile. The can 10 is open at its rear end where it is internally threaded to provide a course 10a extending a substantial distance into the can. A squib block 11 is mounted in the can a substantial distance forwardly from

2

its rear end, the block being of cylindrical form and fitting closely in the can. The block 11 is located axially in the can by a ring 11a threaded in the course 10a and screwed against the front end of the course.

In its rear end portion, the block 11 has an axial bore for receiving a sensitive explosive charge 12, such as lead azide. The charge 12 extends forwardly into a radial recess 13 in the squib block, the recess 13 containing an electrically operable squib 14 which abuts at its inner end against the charge 12. The squib 14 is adapted to be energized through wiring 14a from an electrical control assembly (not shown), such as an assembly of the type disclosed in a copending application of M. A. Tuve et al., Serial No. 471,388, filed January 6, 1943. A self-destruction switch 15 is disposed in the squib block 11 in eccentric relation to the axis of the can 10, the switch 15 being preferably of the movable flat spring type disclosed in a copending application of T. H. Darnell, Serial No. 502,521, filed September 15, 1943. The self-destruction switch 15 and the squib 14 are connected in circuit with the operating components of the electrical control assembly, which is mounted in the forward portion of the can 10.

An auxiliary detonator or booster 17 is disposed in the can 10 to the rear of and in spaced relation to the squib block 11, the booster preferably comprising a block of tetryl or other suitable insensitive explosive. The booster 17 is held in place in the can by a rear end wall 18, made of plastic, or the like, which is screwed into the can.

The azide charge 12 is normally isolated from the booster 17 by the safety device of our invention, shown generally at 20, which is interposed between the booster and the squib block 11. The safety device 20, as shown particularly in Figs. 2, 3 and 4, comprises a cup-shaped housing 21 having side walls which are externally threaded, as shown at 21a, so that the housing may be screwed into the rear end portion of the can prior to insertion of the booster 17 and the end plate 18. The closed end of the housing 21 is disposed adjacent the booster 17 and has an axial opening for receiving a tetryl charge 22. If desired, the closed end of the housing 21 may also have spanner openings 23 for receiving a tool to facilitate insertion of the gate into the can and removal therefrom.

Mounted in the housing 21 adjacent the closed rear end thereof is a body plate 25 which, as shown, is generally cylindrical in form and has a relatively wide, rectangular recess 26 extending inwardly from its periphery and terminating in a relatively narrow slot 27. The plate 25 fits closely in the rear end portion of housing 21 and has a radial protrusion or peripheral lug 28 engaged in a guide groove or recess in the side wall of the

housing to secure the plate against rotation relative to the housing and the can.

The plate 25 serves as a guide for a safety gate 30 which is generally T-shaped, the head 31 of the gate being disposed in the recess 26, and the stem 32 of the gate fitting closely in the slot 27. A weight 33, made of lead, or the like, is secured in a transverse bore in the gate head 31 so that in the normal or innermost position of the gate, the weight is offset from the axis of the can 10. It will be observed that when the gate 30 is in its innermost position in plate 25, a substantial clearance is provided between the gate head 31 and the inner wall of housing 21, so that the gate is adapted to move outwardly under the action of centrifugal force incident to rotation of the projectile and the can 10. Near its inner end, the stem 32 of the gate has a transverse opening for receiving a tetryl charge 34 which, in the innermost position of the gate, is offset from the charge 22.

A second plate 25a is seated in the housing 21 on the front face of the guide plate 25 and serves as a guide for a gate 30a. The guide plate 25a and the gate 30a are similar to the plate 25 and gate 30, respectively, and therefore, a detailed description of them is unnecessary. However, the guide plate 25a is disposed in housing 21 so that its slot 27a and recess 26a are in diametrically opposed relation to the slot 27 and recess 26 of the adjacent plate 25. Accordingly, the gate 30a is movable outwardly in a direction opposite to the direction of movement of gate 30, as will be apparent from a comparison of Figs. 2 and 3. The plates 25, 25a and their corresponding gates 30, 30a are held in the housing 21 against the closed end thereof by means of a cover 35 secured in the open end of the housing, the cover having an axial opening aligned with the azide charge 12.

It will be observed that when the gate 30a is in its innermost position, its tetryl charge 34a is offset radially from the charge 12. Accordingly, in the normal positions of the parts, the tetryl charge 22 is separated from the azide charge 12 by the stems of both of the gates 30 and 30a, so that any accidental explosion of the charge 12 is effectively blocked and prevented from reaching the charge 22 and the booster 17.

In order to lock the gates 30 and 30a in their inner or blocking positions, we provide detents 37 and 37a mounted in transverse bores 38 and 38a, respectively, in plates 25 and 25a. The detents 37 and 37a have reduced inner end portions which normally fit into sockets 39 and 39a in the gate stems 32 and 32a, respectively, the detents being normally held in the sockets by leaf springs 40 and 40a, respectively, mounted in recessed portions of the guide plates. The springs 40 and 40a are of sufficient strength to prevent withdrawal of the detents from the gate sockets 39 and 39a during handling of the projectile.

The operation of the device is as follows: Prior to firing the projectile, the gates 30 and 30a are locked in their innermost positions by detents 37 and 37a, respectively, so that each gate presents a solid portion of its stem in alignment with the charges 12 and 22. However, when the projectile is fired from a gun, centrifugal force incident to rotation of the projectile causes detents 37 and 37a to move outwardly against the action of springs 40 and 40a, with the result that the detents are withdrawn from the sockets 39, 39a and the gates are released. Thereupon, the action of centrifugal force moves the gates 30 and

30a outwardly but in opposite directions in their respective plates 25 and 25a, each gate being guided in its outward movement by the recess and slot 26, 27 in its guide plate. The outward movement of the gates is arrested when their heads 31, 31a engage the side wall of housing 21, and with the gates in their outermost positions, their respective charges 34, 34a are in alignment with each other and with the charges 12 and 22. That is, when the gates move outwardly under centrifugal force, as seen in Fig. 1, the charge 34 of gate 30 moves downwardly into alignment with the adjacent charge 22 in the housing, and the charge 34a in gate 30a moves upwardly into alignment with the adjacent charge 12 in the squib block, the gates being maintained in these positions by centrifugal force as the projectile rotates. Thus, when the squid 14 is detonated electrically through the wiring 14a, it fires the booster 17 through the charges 12, 34a, 34 and 22, and the booster 17 detonates the main charge (not shown) in the projectile.

The charge 34 in the gate adjacent booster 17 should be made of tetryl or other insensitive explosive, while the charge 34a in the gate adjacent the squib block 11 should be made of lead azide or other sensitive explosive. In this connection, it has been found that when an azide charge 34a is used, there is no need for the azide charge 12 in the squib block. In other words, an azide charge should be placed between the squib and the tetryl charge 34 in the rear gate 30, but this charge may be placed either in the squib block 11, as shown at 12, or in the front gate 30a.

It will be apparent that the safety device of our invention is simple and compact in construction and employs relatively few moving parts. By reason of the double gate assembly 30 in the housing 21, the device has a high factor of safety and may be subjected to rough handling without arming the fuze. An important feature of our invention is that the device will operate satisfactorily even though its axis is offset from the axis of rotation of the projectile as much as one-eighth of an inch.

We claim:

In a fuze mechanism for use in a spinning projectile, the combination with a cylindrical housing, a pair of guide plates each having a centering lug engaging an inner groove of the housing, and said plates each fashioned with a diametrical slot, each said slot having a transverse recess, of a pair of charge-carrying gates each having a cross head formed with a transverse bore, a weight in the bore, said gates movable in the slots and recesses under centrifugal force in opposite directions for aligning an initially interrupted explosive train, and means for holding the gates in initial positions and operable under centrifugal force for releasing the gates.
